(57) **CLAIM**

The ornamental design for a fastener component, as shown and described.

DESCRIPTION

FIG. 1 is a perspective view of a fastener component, showing our new design.

FIG. 2 is a side elevation view of the fastener component of FIG. 1.

FIG. 3 is another side elevation view of the fastener component of FIG. 1.

FIG. 4 is another side elevation view of the fastener component of FIG. 1.

FIG. 5 is another side elevation view of the fastener component of FIG. 1; and,

FIG. 6 is a top view of the fastener component of FIG. 1.

In the drawings, the broken lines form no part of the claimed design.
